BUCKLE

Walter S. Painter, Middlebury, Conn., assignor to
 Waterbury Buckle Company, Waterbury, Conn.,
 a corporation of Connecticut

Application February 18, 1939, Serial No. 257,162

3 Claims. (Cl. 24—191)

This invention relates to buckles and more especially to sheet-metal buckles of a type primarily intended for use on suspenders, garters, and the like and commonly known as adjusting-buckles.

One object of the present invention is to provide an improved construction for sheet-metal buckles whereby the wear and tear on the wearer's garments due to the rubbing-engagement of the buckles therewith may be reduced to a minimum and, by means of which, bodily discomfort to the wearer may be avoided.

In pursuance of the foregoing object, the invention contemplates an improved construction and arrangement of parts in a sheet-metal buckle comprising articulately-connected body- and bent-lever members whereby the rubbing-contact between the buckle and the wearer's apparel is confined to a smoothly-continuous surface of one of the articulately-connected members of the sheet-metal buckle.

Another object of the invention is to provide an improved coupling-connection between the body-member and bent-lever member of a sheet-metal buckle wherein the articulating-connections are arranged between and substantially-enveloped by the smooth imperforate walls of the said buckle members which, in their strap-gripping position, are arranged in closely-interfitting relation to each other to provide smoothly-continuous surfaces and rounded corners and edges in and around those portions of the buckle which are subjected to rubbing-engagement with the garment or person of the wearer.

With the above and other objects in view, as will appear to those skilled in the art from the present disclosure, this invention includes all features in the said disclosure which are novel over the prior art.

In the accompanying drawing:

Fig. 1 is a view in front elevation of a buckle constructed of sheet-metal and of a type intended primarily for use on suspenders and other garment-supporters, the buckle being shown as applied to a suspender-strap;

Fig. 2 is a view in side elevation thereof;

Fig. 3 is a top plan view thereof;

Fig. 4 is an enlarged view in vertical medial section taken on the line 4—4 of Fig. 1;

Fig. 5 is a similar view, the buckle being removed from the suspender-strap, with the body-member shown in open relation to the bent-lever member;

Fig. 6 is a perspective view of the body-member of the sheet-metal buckle removed; and

Fig. 7 is a perspective view of the sheet-metal bent-lever member removed.

The sheet-metal buckle may be of any desired construction suitable for adaptation to the purposes of the present invention and, in the form herein shown for illustration, comprises a front or body-member which is generally designated by the reference character 10; and a rear or bent-lever member generally designated by the reference character 11.

As shown particularly well in Fig. 6, the body-member 10 comprises a front plate 12 which is bowed forwardly, as shown in Fig. 4, to provide a curved inner wall 13 extending between laterally-spaced imperforate side-plates 14—14 extending from an upper curved marginal-flange 15 at the top of the front plate 12 to a lower curved marginal-flange 16 at the bottom of said front plate 12. The rear edges of said upper and lower marginal-flanges 15 and 16 are arranged substantially in a common plane with respect to which the strap-gripping lever-arm of the bent-lever is in parallelism in one of its extreme positions and past which it projects beneath the upper curved marginal-flange 15 in its other extreme position.

The imperforate side-plates 14—14 according to the embodied form of the invention shown in the drawing, are generally rectilinear in profile and have their rear edges 17—17 arranged in a common plane substantially parallel to the common plane of the upper and lower marginal-flanges 15 and 16 of the body-member 10. Integrally-formed with the side-plates 14—14 and projecting inwardly therefrom at the rear edges thereof are pintles or tongues 18—18 which are deflected inwardly into transverse alignment. The said tongues or pintles 18—18 are disposed slightly below the upper edges of the side-plates 14—14 to provide stop-shoulders 19—19 for limiting the clockwise oscillatory movement, as viewed in the drawing, of the body-member 10 with respect to the bent-lever member 11.

The bent-lever member 11 comprises a suspension-lever arm generally designated by the reference character 20 and a gripper-lever arm which is generally designated by the reference character 21, the said lever-arms being integrally united at and by a right-angled bend 22 which intervenes between and substantially defines the said lever-arms with respect to each other.

The suspension-lever arm 20, as shown particularly well in Figs. 4, 5 and 7, comprises a back plate 23 and a lower end-portion 24 which

is deflected slightly from the plane of the back plate 23 to be disposed in a vertical position when the buckle is in use. The deflected lower end portion 24 of the suspension-lever arm 20 is provided with a transverse slot 25 which, in effect, forms a strap-attaching or suspension-bar 26 at the bottom of the bent-lever member 11. The gripper-lever arm 21, if desired, may be provided with marginal serrations 27 for effecting a more secure grip on the strap or web interposed between said serrations 27 and the curved inner wall 13 of the front plate 12 below the upper curved marginal-flange 15 of the body-member 10 when the buckle is in use.

Arranged on opposite sides of the gripper-lever arm 21 at the intermediate bend 22 are two circular bearing-loops 28 formed of sheet-metal tongues which have their inner circumferential walls arranged substantially tangential to the flat inner surfaces of the lever-arms 21 and 23 to receive the pintles 19-19 at the rear edges of the oppositely-arranged side-plates 14-14.

The laterally-spaced stop-shoulders 19-19 formed at the upper rear corners of the imperforate side-plates 14-14 are arranged, as shown particularly well in Fig. 5, to be brought into abutment with laterally-spaced stop-shoulders 30-30 formed in the lateral edges of the back plate 23 at the upper end of suspension-lever arm 20 at the outer sides of circular bearing-loops 28-28, to thus limit the clockwise movement of the body-member 10, as viewed in the drawing.

As shown in Fig. 5, before the sheet-metal buckle has been assembled in position on a strap or web, the body-member 10 of said buckle is moved in a clockwise direction, according to Fig. 5, until the laterally-spaced stop-shoulders 19-19 at the upper rear corners of the laterally-spaced side-plates 14-14 are brought into engagement with the stop-shoulders 30-30 adjacent the bearing-loops 28-28, the said body-member 10 being thus arrested in the open position shown in Fig. 5. In this arrested position, the common plane of the rear edges of upper and lower marginal-flanges 15 and 16 are arranged substantially parallel to the gripper-lever arm 21 so that the end of a strap 31 may be readily passed over the upper surface of the gripper-arm 21, passed downwardly over the serrated forward marginal edge thereof and, for example, after being threaded through the upper loop of a suspender-tug connection (not shown), the said suspender-strap 31 may be threaded through the transverse slot 25 in the deflected lower end 24 of the suspension-lever arm 20 and connected to itself to form a permanent loop 32 about the suspension-bar 26 of the suspension-lever arm 20.

From the foregoing, it is readily seen that the adjusting-buckle comprises sheet-metal body and lever-members pivotally-connected by interengaging pintles and bearing-loops which are encased within the said buckle-members and thereby prevented from coming into contact with the person or wearing apparel of the user while, at the same time, avoiding the placement of these parts in such a way that they would constitute projections or irregularities on the exterior walls of the buckle where they would be likely to snag and tear articles of wearing apparel.

It is apparent, furthermore, that the construction and arrangement of parts described above contributes materially to simplicity of design; adaptation of outward form to the mechanical purposes of the buckle; and hence conduces to

neatness of appearance and ornamental appeal. The buckle, in its entirety, when closed and in use has an inherent continuity in form and outline; presents smooth and unbroken exterior surfaces and rounded contours; and, in consequence, 5 renders the outer wall of the buckle practically devoid of sharp angles and projections.

A very desirable feature of the buckle resides in the provision of an unbroken and smoothly-continuous rubbing surface on the back plate of 10 the buckle to which the contact between the buckle and the person or wearing apparel of the user is confined.

The invention may be carried out in other specific ways than those herein set forth without departing from the spirit and essential characteristics of the invention, and the present embodiments are, therefore, to be considered in all respects as illustrative and not restrictive, and all changes coming within the meaning and 20 equivalency range of the appended claims are intended to be embraced therein.

I claim:

1. In an adjustable suspender buckle, the combination with a body-member having laterally-spaced side-plates provided at the upper rear corners thereof with coaxially-arranged inturned pintles; of a bent-lever member having a gripper-arm and an angularly-related suspension-arm, the said bent-lever being also provided with 15 coaxially-arranged bearing-loops located at the bend therein and pivotally mounted upon the said pintles, the said bearing-loops being positioned in inwardly-spaced relation to the lateral edges of the said suspension-arm, the said gripper-arm of 30 the bent-lever projecting forwardly from between and substantially in tangential relation to the said bearing-loops, and the said lateral edges of the said suspension-arm projecting laterally outside of the said bearing-loops substantially- 40 flush with the oppositely-presented outer surfaces of the said side-plates and extending downwardly past and below the bottom extremity of the said body-member.

2. A suspender buckle, comprising: a body- 45 member having a front-plate provided with top and bottom arcuate flanges and oppositely-arranged side-plates centrally disposed with respect to the said arcuate flanges and presented rearwardly from the said front-plate, the said side-plates being provided at their rear edges adjacent the upper edges thereof with oppositely-arranged inwardly-presented pintles; and a bent- 50 lever member having a gripper-arm and an angularly-related suspension-arm, the said bent- 55 lever being also provided with coaxially-arranged bearing-loops located at the bend therein and pivotally mounted on the said pintles, respectively, the said bearing-loops being positioned in inwardly-spaced relation to the lateral edges 60 of the said suspension arm and having their outer ends in oscillatable engagement with the opposite inner surfaces of the said side-plates, the said gripper-arm projecting forwardly from between and at the top of said bearing-loops, and the said suspension-arm extending downwardly 65 from the said bearing-loops past the bottom arcuate flange on the front-plate and terminating in a strap-suspension bar below the bottom arcuate flange on the said front-plate, the said suspension-arm being extended laterally outside of the said bearing-loops of the bent-lever member and across the rear edges of the side-plates of 70 the said body-member and having its lateral 75

edges substantially flush with the outer surfaces of the said side-plates.

3. A buckle, including: a body-member having a front-plate provided with rearwardly-presented top and bottom marginal flanges terminating rearwardly in a common plane and having rearwardly-presented side-plates extending rearwardly past and closing the end spaces between the said top and bottom marginal flanges, the said side-plates having at their rear edges, and adjacent their upper edges, coaxially-arranged pintles extending inwardly therefrom, the said pintles being spaced from the upper edges of the said side-plates, and the rear edges of the side-plates between the upper edges thereof and the said pintles providing stop-shoulders for the said body-member; and a bent-lever member comprising a strap-suspension arm hav-

ing its opposite lateral edges disposed substantially-flush with the outer surfaces of the said side-plates, coaxially-arranged bearing-loops inset from the lateral edges of the said suspension-arm and pivotally mounted on the said pintles, with their outer ends in rotational abutment with the inner surfaces of the said side-plates, and a gripper-arm extending forwardly from between the said bearing-loops and past the said terminal plane of the top and bottom marginal flanges on the said front-plate, the upper portions of the said bent-lever member extending from the bearing-loops thereof to the lateral edges of the said strap-suspension arm providing cooperating stop-shoulders engageable by the stop-shoulders of the said body-member.
